CLAIM

I claim the ornamental design for a device case, as shown
and described.

DESCRIPTION

FIG. 1 is an isometric front view of a device case;
FIG. 2 is an isometric rear view of the device case from the
lower right side;

FIG. 3 is an isometric rear view of the device case from the
upper left side;

FIG. 4 is a front view of the device case;

FIG. 5 is a left side view of the device case;

FIG. 6 is a right side view of the device case;

FIG. 7 is a top view of the device case;

FIG. 8 is a bottom view of the device case; and,

FIG. 9 is a rear view of the device case.

The broken lines depict portions of the device case that form
no part of the claimed design.

1 Claim, 7 Drawing Sheets
